[57] CLAIM

The ornamental design for a recoil controller for firearms, as shown and described.

DESCRIPTION

FIG. 1 is a perspective view of a recoil controller for firearms, showing my new design.

FIG. 2 is a front elevational view.

FIG. 3 is a side elevational view.

FIG. 4 is a top plan view.

FIG. 5 is a bottom plan view; and

FIG. 6 is a rear end view.

The side elevational view not shown is the same as FIG. 3.

Fig.1.

Fig.2.
